US00D945310S

(12) **United States Design Patent** (10) **Patent No.:** **US D945,310 S**
Davis, Jr. (45) **Date of Patent:** **** Mar. 8, 2022**

(54) **TURF FIBER**

(71) Applicant: **GO GREEN SYNTHETIC LAWN SOLUTIONS, LLC**, Tunnel Hill, GA (US)

(72) Inventor: **David M. Davis, Jr.**, Tunnel Hill, GA (US)

(**) Term: **15 Years**

(21) Appl. No.: **29/718,108**

(22) Filed: **Dec. 20, 2019**

(51) LOC (13) Cl. **11-04**

(52) U.S. Cl.

USPC **D11/117**

(58) **Field of Classification Search**
